UNITED STATES PATENT OFFICE.

SAMUEL N. LONG, OF ST. LOUIS, MISSOURI, ASSIGNOR TO THE S. N. LONG SYRUP COMPANY, OF SAME PLACE.

HERMETICALLY-SEALED BUCKET.

SPECIFICATION forming part of Letters Patent No. 510,867, dated December 12, 1893.

Application filed June 5, 1893. Serial No. 476,684. (No model.)

To all whom it may concern:

Be it known that I, SAMUEL N. LONG, of the city of St. Louis, in the State of Missouri, have invented a certain new and useful Improvement in Hermetically-Sealed Buckets, of which the following is a full, clear, and exact description, reference being had to the accompanying drawings, forming part of this specification.

10 My invention relates to a device for hermetically sealing buckets employed for holding sirups, or other canned goods, which it is necessary to keep air tight, in order that the goods may not become deteriorated through 15 the contact of air.

There is generally in receptacles containing canned goods, a total loss of the receptacle when the original contents have been removed, and it is the object of my invention 20 to provide a package that is of utility after the package has been opened and the original contents have been removed, and to form a receptacle that is to all intents and purposes as serviceable for further use after the hermetical sealing is removed, as if it were originally produced for the secondary purpose for 25 which it is intended.

My invention consists in features of novelty hereinafter fully described and pointed out in 30 the claim.

Figure I is a side elevation of a bucket, provided with my improved hermetical sealing device, as it appears after sealing. Fig. II is a view, showing the upper portion of the 35 bucket in vertical section, and the packing strip only applied, and showing the filling opening, with cap removed. Fig. III is a detail view showing the upper portion of the bucket in vertical section, and the lid inserted, as it appears when the sealing strip 40 has been removed, to illustrate the use of the bucket as an ordinary vessel, after the original contents have been removed. Fig. IV is a detail, vertical section through the upper 45 portion of the bucket and the lid, showing the packing strip alone in position. Fig. V is a similar view to Fig. IV, with the addition of the sealing strip; and Fig. VI is a similar 50 view to Fig. V, in which is shown the strips of solder or other sealing material applied to the sealing strip.

Referring to the drawings, 1 represents the bucket formed with a top bead 2, and provided with a usual bail 3, connected to the bucket by ears 4.

5 is the lid provided with a wide, depending flange 6, the lower portion only of which flange fits within the bucket when the sealing strip is applied, and 7 is a horizontal flange to the lid.

The device for hermetically sealing the vessel consists of a thin strip 8, preferably of tin, between which and the flange 6 is a strip 9 of packing to form a tight connection between the sealing strip and the flange. At 65 its upper and lower edges, I secure the strip 8 by strips 10 of solder, the upper strip connecting the sealing strip, and the flange 7, and the lower strip connecting the sealing strip and the bead 2 of the bucket. One end 70 of the sealing strip overlaps the other end, leaving a projecting portion 11, which may be grasped by a suitable tool, for the purpose of removing the strip.

The sealing device is applied in the manufacture of the bucket, and I provide an opening 12 in the lid of the bucket, through which the goods to be preserved are inserted into the vessel, after which the opening is closed by a cap 13, secured by a strip 14, of sealing 80 material.

By my invention I provide a vessel that is admirably adapted for the preservation of canned goods, and which, when it has been opened, leaves the bucket in a very serviceable condition for future use, and without objectionable or unsightly projections on the vessel or lid.

I claim as my invention—

In a hermetically sealed bucket, the combination with the bucket, of a lid provided with a depending flange, said flange being adapted to but partially enter the bucket, a sealing strip surrounding said flange and soldered to the bucket and lid, and a packing strip interposed between said sealing strip and depending flange; substantially as described.

SAMUEL N. LONG.

In presence of—

E. S. KNIGHT,
A. M. EBERSOLE.
